(57) **CLAIM**

The ornamental design for a combined hydration pack cap and mount, as shown and described.

DESCRIPTION

FIG. 1 is a perspective view of a combined hydration pack cap and mount showing out new design, it being understood that the broken line disclosure of a pack and hose is for illustrative purposes only and forms no part of the claimed design;

FIG. 2 is an enlarged and exploded perspective view illustrating the cap removed from the mount of our new design; FIG. 3 is a top plan view of the mount of FIG. 2 shown alone for ease of illustration;

FIG. 4 is a bottom plan view of the mount of FIG. 2; FIG. 5 is a right side elevation view of the mount of FIG. 3, the left side elevation view being a mirror image of the view shown;

FIG. 6 is a cross-sectional view of the mount taken along line 6—6 in FIG. 3;

FIG. 7 is a front elevation view of the mount of FIG. 3;

FIG. 8 is a rear elevation view of the mount of FIG. 3; FIG. 9 is a top plan view of the cap of FIG. 2 shown alone for ease of illustration;

FIG. 10 is a bottom plan view of the cap of FIG. 2;

FIG. 11 is a rear elevation view of the cap of FIG. 9;

FIG. 12 is a front elevation view of the cap of FIG. 9;

FIG. 13 is a left side elevation view of the cap of FIG. 9; and, FIG. 14 is a right side elevation view of the cap of FIG. 9.
